STOCK QUOTATION PROJECTING MACHINE

August D. Eitzen, Rockville Centre, N. Y., assignor to News Projection Corporation, New York, N. Y., a corporation of New York

Application April 9, 1932, Serial No. 604,216
Renewed August 28, 1937

27 Claims. (Cl. 271—2.3)

This invention relates to, and has for a main object to produce, an improved stock quotation projecting machine in which the motor is continuously operating and the tape pulling device becomes inoperative when the ticker stops.

It is still another object of the present invention to provide an improved stock quotation projecting machine in which the control for the pulling sheave is all contained in the sheave itself, thereby reducing the space ordinarily required for such control to a minimum and as in this case completely saving such space.

It is still another object of the present invention to produce an improved slip clutch device for the tape pulling sheave of a stock quotation projecting machine in which the sheave is mounted freely to rotate on the driven shaft, a stationary clutching element is fixed to said shaft, a movable clutching element is connected to the sheave and means are provided for normally and yieldably causing said clutching elements to clutchingly engage one another.

It is still another object of the present invention to provide an improved stock quotation projecting machine in which a slip clutch control pulling sheave will cooperate with a tape vibration dissipating device to facilitate said device in following up the slack in the tape to iron out the vibrations transmitted thereto and to definitely anchor the pulling sheave against rotation when the ticker is at rest so as to relieve the tape of any undue strain during this period of rest.

These and other features, capabilities and advantages of the invention will appear from the subjoined detail description of specific embodiments thereof illustrated in the accompanying drawings in which

Figure 1 is a side elevation of a machine equipped according to one embodiment of the invention;

Fig. 2 is an end elevation enlarged of the tape pulling mechanism;

Fig. 3 is a transverse section substantially on the line 3—3 of Fig. 4 still further enlarged showing the clutch in detail;

Fig. 4 is an enlarged section on the line 4—4 of Fig. 3 showing the clutch in gripping engagement;

Fig. 5 is a section similar to the section of Fig. 4 showing the clutch out of gripping engagement;

Fig. 6 is a side elevation of a machine equipped with another embodiment of the present invention;

Fig. 7 is an enlarged fragmental side elevation of a part of the tape control mechanism; and

Fig. 8 is an enlarged fragmental end elevation of the tape control mechanism of this embodiment.

In the embodiment illustrated in Figs. 1 to 5 inclusive, there is shown a stock quotation projecting machine having a ticker of the high speed type illustrated as enclosed in the casing 1 from which the tape T passes under the finger 2 to the roller 3 at the entrance end to the light aperture formed on the extension 4 of the lamp housing 5 from which the tape T passes over the roller 6 and then down around the tape pulling roller on sheave 7 mounted to freely rotate on the shaft 8 of the reduction gearing contained in the housing 9 from which the tape T passes to the rewind reel 10.

The shaft 8 has fixed thereon and disposed in the housing 9 a worm wheel 11 in mesh with the worm 12 mounted on the shaft 13 extending at right angles to the shaft 8 and journaled in the housing 9 below the shaft 8. The shaft 13 is provided with a pulley 14 connected to the pulley 15 of the motor 16 by the belt 17.

The shaft 8 has formed on the outside of the housing 9 a pulley 18 connected to the pulley 19 by the spring belt 20, the pulley 19 being mounted on the shaft 21 journaled in the bearing 22 at the upper end of the arm 23, the rewind reel 10 being secured to said shaft 21, as illustrated in Fig. 2.

The finger 2 in the present embodiment is formed at the end of an extended arm or lever 24 pivotally connected to the bracket 25 extending upwardly from the extension 4. Such arm 24 preferably has a weight 26 adjustably mounted thereon to facilitate controlling the tension on the tape T by the finger 2.

Extending upwardly from the housing 5 is formed the bracket 27 at the upper end of which is mounted the housing 28 for the objective lens which receives the images formed of the characters on the tape and directs them upwardly to the mirror 29 which in turn deflects them onto the mirror 30 which in turn deflects them onto the screen 31.

The main part of the present invention consists essentially of the clutching mechanism for the tape puller or sheave 7 and its cooperation with the finger 2. This clutching mechanism consists essentially of a fixed clutching element 32 and a movable clutching element 33. The fixed clutching element, see particularly Figs. 3, 4, and 5 consists of a drum 34 having a hub 35 fixed to

the shaft 8 by the pin 38. The movable clutching element consists of an arcuate finger pivotally connected to the disc 37 also mounted to rotate freely on the shaft 8.

5 This movable clutching element has an inwardly extending projection 38 having an arcuate inner face disposed to engage the periphery of the drum 34 when in clutching engagement therewith. This clutching face of the projection 38 is normally and yieldably maintained in engagement with the periphery of the drum 34 by the spring 39 extending from the pin 40 near the free end of the finger 38 to the pin 41 extending laterally from the disc 37. The extreme 10 end of the finger 38, to wit the portion 42 is adapted to engage the pin 43 extending inwardly from the inner periphery of the cylindrical wall 44 of the sheave 7.

From the foregoing, it will be seen that the 20 clutch control or clutching mechanism will have different angular movements relative to the drive shaft and the tape puller 7, see particularly Fig. 4, when the tape T is being discharged by the ticker and free to be drawn in the direction of the arrow 45, the spring 39 will be free to thrust the pin 43 and therewith the sheave 7 out of its way to permit its projection 38 clampingly to engage the drum 34 and travel with the drum 34 which is driven by the shaft 8 in one angular 25 relation in the direction of the arrow 45 in Fig. 4 or the arrow 46 in Fig. 3.

On the other hand, if the ticker stops, the 30 reaction of the tape T will be in the direction of the arrow 47 in Fig. 5 whereupon the pin 43 will engage the end 42 of the finger 38 to oppose the action of the spring 39 in turn to cause the friction face of the projection 38 to permit the drum 34 to slip relative to said projection 38 in another angular relation.

40 The sheave 7 as illustrated in Fig. 3 is preferably composed of two parts as illustrated, one having the disc portion 48 integral with the cylindrical wall 44 and having an annular flange 49 at its edge, and the other having a disc portion 50 with a shouldered recess 51 formed to frictionally receive the end of the cylindrical wall 44 and provided with a flange 52, the tape T engaging the outer periphery of the wall 44 and being guided in position on the sheave 7 by the 45 flanges 52 and 49.

For causing the sheave 7 to drivingly engage the tape T, the roller 53 is provided, it being journaled in the bracket 54 pivoted at 55 and provided with the arm 56 on which is adjustably 50 mounted the weight 57, the roller 53 frictionally pressing the tape T into engagement with the sheave 7.

In the embodiment illustrated in Figs. 6, 7 and 8, the tape pulling sheave is practically identical 60 with the tape pulling sheave 7 of the embodiment illustrated in Fig. 1 arranged however in this instance to permit the tape to move over the upper face thereof and equipped to cooperate with the vibration dissipating lever.

65 The tape T' in this instance passes from the ticker, preferably of the high speed type contained in the housing 58 to the light aperture disposed on the extension 59 of the lamp housing 60 and then passes over the tape pulling sheave 61 in engagement with which the tape is maintained by the idler 62. From the tape pulling sheave 61, the tape passes down under the idler 63 mounted on the side of the housing 64 and then passes over to the rewind reel 65 mount-

ed on the shaft 66 journaled in the end of the bracket 67 extending from the housing 64.

At the entrance and discharge ends of the light aperture, there are formed the rollers 68 and 69 as indicated to facilitate the movement of the 5 tape across such light aperture. Between the ticker and the roller 68, the finger 70 of the lever 71 engages the upper face of the tape T'. The lever 71 then extends across the extension 59 to the link 72 to which it is pivotally connected and 10 which in turn is pivotally connected at 73 to the upper end of the housing 64, the lever 71 and link 72 thus forming and serving as a split lever. The link 72 is provided with a small recess 74 to receive the pin 75 extending from the side of the 15 housing 64, the cooperation of the pin 75 with the ends of the slot 74 determining the limit of movement of the link 72. For yieldably maintaining the link 72 in raised position with the lower end of its slot 74 in engagement with the pin 75, there 20 is provided the spring 76.

The lever 71 is provided with a short arm 77 having a downwardly extending finger 78 provided with a flaring face 79. The finger 78 is adapted to engage the teeth 80, four in number 25 in the present instance, extending from the disc 81, constituting a rotative element, which forms a guiding flange for the tape T' on the sheave 61. The sheave 61 is similar to the sheave 7 of the embodiment illustrated in Fig. 1, and has 30 a cylindrical housing 82 which in the present instance extends from the disc 81 and has secured thereto the disc 83 to form the other guiding flange for the tape T' passing over such sheave 61.

The discs 81 and 83 of the sheave 61 are mounted 35 on the shaft 84 which in the present instance is the driven shaft journaled in the housing 64 having fixed thereon the worm wheel 85 in mesh with the worm 86 fixed on the shaft 87 journaled in the housing 64. On the outwardly extending 40 end of the shaft 87, there is fixed the pulley 88 which is connected to be driven by the pulley 89 by the belt 90. The pulley 89 is fixed on the shaft 91 of the motor 92.

On the shaft 84, there is also secured the pulley 93 which is connected to drive the pulley 94 on the shaft 66 of the reel 65 by means of the 45 spring belt 95.

The pressure roller 62 for maintaining the tape T' in driving engagement with the sheave 61 is 50 preferably journaled in the end of the bracket 96 having the extension 97 and pivotally connected to the housing 64 by the pin 98. For maintaining the roller 62 in such driving engagement, the spring 99 is provided connecting the extension 97 with the abutment 100 extending from the housing 64. The sheave 61 is drivingly connected to the shaft 84 by the clutching device illustrated in detail of Fig. 3 of the first described embodiment. It has a drum 101 extending from the shaft 84 and fixed to rotate therewith. Freely rotatable on the shaft 84 inside of the sheave 61, there is mounted the disc 102 which has pivotally connected thereto the arcuate lever 103 which has a clutching projection 104 formed thereon which is resiliently maintained in engagement with the periphery of the drum 101 by the spring 105. When the tape T' is being discharged by the ticker and it is free to be taken up by the pulling sheave 61, the spring 105 will first move the sheave in the direction of rotation by the cooperation of the pin 106 extending from the cylindrical portion 82 with the lever 103 whereupon the clutching face 104 of the 55 60 65 70 75 80 85 90 95 100 105 110 115 120 125 130 135 140 145 150 155 160 165 170 lever 103 will engage the drum 101 to cause the sheave 61 to turn with the shaft 84.

From the foregoing, it will also be seen that when the ticker comes to rest and no further tape is being discharged from it for the moment, the pulling sheave 61 will continue to draw the tape across the light aperture and thereby take up the slack under the finger 70, in turn to cause the finger 78 to be depressed into the path of movement of one of the teeth 80, see the initial contact illustrated by the dash and dot line in Fig. 7. The sleeve 61 will thereupon draw the finger 78 with it against the tension of the spring 76 and cause the finger 78 to ride up on the tooth 80, see the full line position in Fig. 7, as compared to the dash and dot line position of that figure. This extended action of the finger 78 will cooperate with the sheave 61 to counteract the jar that might otherwise be transmitted to the tape by the sudden engagement of the finger 78 with the tooth 80 and thus cause a slight retardation in the drawing action of the tape before finally coming to rest.

This flexible action between the finger 78 and tooth 80 will also cooperate with the friction clutch contained in the sheave 61 to produce a smooth and even start and stop of the tape and to insure the formation of a loop sufficiently large under the finger 70 so that the stopping of the pulling sheave will overlap at least two and possibly three printing impulses so that in turn the starting and stopping of the pulling sheave will not correspond to the insignificant starting and stopping of the tape with each printing impulse and that as a result thereof the sheave will only come to rest when the ticker has come to rest after the transmission of a message or a series of characters where the interruptions or arrest of the tape exceeds the time interval required to print at least two characters and preferably three characters.

It is obvious that various changes and modifications may be made to the details of construction without departing from the general spirit of the invention as set forth in the appended claims.

I claim:

1. In a tape control device for a stock quotation projection machine, the combination with a driving shaft, of a tape pulling sheave rotatably mounted on said shaft, a lever responsive to deflections in the tape anterior to the tape pulling sheave having one arm disposed to engage the tape and the other arm adapted to engage the sheave to anchor it against rotation when the discharge of the tape is interrupted, and a floating clutch angularly movable independent of said sheave and driving shaft but normally anchoring said sheave to said driving shaft and yieldable to release said sheave when the discharge of the tape is arrested.

2. In a tape control device for a stock quotation projection machine, the combination with a driving shaft, of a pulling sheave rotatably mounted on said shaft and having a toothed flange, a lever responsive to deflections in the tape having one arm disposed to engage the tape and the other arm adapted to engage the toothed flange of the sheave to anchor it against rotation when the discharge of the tape is interrupted, and a floating clutch rotatable independent of said sheave and driving shaft but normally anchoring said sheave to said driving shaft and yieldable to release said sheave when anchored by said lever.

3. In a tape control device for a stock quotation projection machine, the combination with a driving shaft, of a tape pulling sheave rotatably mounted on said shaft, a pivotally mounted link, a lever pivotally connected to said link and having one arm disposed to engage the tape and the other arm adapted to engage the sheave to anchor it against rotation when the discharge of the tape is interrupted, and a floating clutch angularly movable independent of said sheave and driving shaft but normally anchoring said sheave to said driving shaft and yieldable to release said sheave when the discharge of the tape is arrested. 5

4. In a tape control device for a stock quotation projection machine, the combination with a driving shaft, of a tape pulling sheave rotatably mounted on said shaft, a pivotally mounted link, a lever pivotally connected to said link and having one arm disposed to engage the tape and the other arm adapted to engage the sheave to anchor it against rotation when the discharge of the tape is interrupted, and a spring operatively connected to said link to cause said lever yieldably to oppose the rotation of said sheave when engaging said lever. 15

5. In a tape control device for a stock quotation projection machine, the combination with a driving shaft, of a tape pulling sheave rotatably mounted on said shaft, a lever responsive to deflections in the tape having one arm disposed to engage the tape and the other arm adapted to engage the sheave to anchor it against rotation when the discharge of the tape is interrupted, a link on which said lever is pivotally mounted, a slot and pin connection for limiting the movement of said link, a spring for yieldably anchoring said link in one extreme position but yieldable to permit said link to move in the other extreme position when said lever is engaged by said sheave, and a floating clutch normally anchoring said sheave to said driving shaft but yieldable to release said sheave when the discharge of the tape is arrested. 30 35

6. In a tape control device for a stock quotation projection machine, the combination with a driving shaft, of a hollow tape pulling sheave rotatably mounted on said shaft, and a floating clutch disposed in said sheave rotatable independent of said sheave and shaft but normally anchoring said sheave to said driving shaft and yieldable to release said sheave when the discharge of the tape is arrested. 40

7. In a tape control device for a stock quotation projection machine, the combination with a driving shaft, of a tape pulling sheave rotatably mounted on said shaft, a drum fixed to said shaft, a disc rotatably mounted on said shaft, an arcuate arm pivotally connected to said disc and having a clutching projection formed thereon, a spring for frictionally maintaining said clutching projection in clutching engagement with said drum, and a projection formed on said sheave cooperating with said arm to cause said arm to clear said drum when the discharge of the tape is arrested. 55 60 65

8. In a tape control device for a stock quotation projection machine, the combination with a driving shaft, of a hollow tape pulling sheave rotatably mounted on said shaft, a clutching drum fixed to said shaft and disposed in said sheave, and a yieldable clutching lever disposed in said sheave angularly movable independent of said sheave and driving shaft but normally connecting said sheave to said drum and yield- 70 75

able to release said sheave when the discharge of the tape is arrested.

9. In a tape control device for a stock quotation projection machine, the combination with 5 a driving shaft, of a tape pulling sheave rotatably mounted on said shaft, a drum fixed to said shaft, a disc rotatably mounted on said shaft, an arcuate arm pivotally connected to said disc and having a clutching projection formed there- 10 on, a spring for frictionally maintaining said clutching projection in clutching engagement with said drum, and a projection formed on said sheave and disposed in the path of movement of said arm, said arm engaging said projection 15 to rotate said sheave with said drum when in clutching engagement and cooperating with said projection to clear said drum when said sheave is anchored against rotation.

10. In a tape control device for a stock quota- 20 tion projection machine, the combination with a continuously driven drive shaft, of a tape pulling sheave, a slip clutch normally drivingly connecting said sheave to said drive shaft, a lever responsive to deflections in the tape having one 25 arm disposed to engage the tape and the other arm adapted to engage the sheave, a link on which said lever is pivotally mounted, and means including a spring operatively connected to said link for normally maintaining said lever out of 30 engagement with said sheave but yieldable to permit a deflection in the tape to actuate said lever into engagement with said sheave to produce a gradually increasing retarding effect on said sheave.

11. In a tape control device for a stock quota- 35 tion projection machine, the combination with a continuously operating drive shaft, of a tape pulling sheave, a slip clutch normally drivingly connecting said sheave to said shaft, a split lever having an arm in engagement with the tape and responsive to deflections therein, and means includ- 40 ing a spring operatively connected to the other arm of said split lever for normally maintaining said split lever out of engagement with 45 said sheave but yieldable to permit a deflection in the tape to actuate said split lever into engagement with said sheave to produce a gradually increasing retarding effect on said sheave.

12. In a tape control device for a stock quota- 50 tion projection machine, the combination with a continuously driven drive shaft, of a tape pulling sheave, a slip clutch normally drivingly connecting said sheave to said drive shaft, a split lever having one portion thereof disposed in engagement with the tape and responsive to deflections therein, and control means connected to another portion of said split lever and yieldable to permit the portions of said split lever to move relative to one another when actuated by a deflection in the tape to engage said sheave and produce a gradually increasing retarding effect on the same.

13. In a tape control device, the combination with a driving shaft, of a tape pulling sheave rotatably mounted on said shaft, and means includ- 65 ing a floating clutch member interposed between said driving shaft and said sheave said floating clutch member being angularly movable independent of and concentric with, said sheave and driving shaft, said means normally cooperat- 70 ing to anchor said sheave to said driving shaft and yieldable to release said sheave when the discharge of the tape is arrested and again to anchor said sheave to said shaft when the dis- 75 charge of the tape is resumed.

14. In a tape control device, the combination with a tape pulling sheave, of a pivotally mounted link, a lever pivotally connected to said link and having one arm disposed to engage the tape and the other arm adapted to engage the sheave 5 and to anchor it against rotation when the discharge of the tape is interrupted, and a spring operatively connected to said link to cause said lever yieldably to oppose the rotation of said sheave when engaging said lever.

15. In a tape control device, the combination with a tape pulling sheave, of a lever responsive to deflections in the tape having one arm disposed to engage the tape and the other arm adapted to engage the sheave to anchor it against 15 rotation when the discharge of the tape is interrupted, a link on which said lever is pivotally mounted, a slot and pin connection for limiting the movement of said link, and a spring for yieldably anchoring said link in one extreme position 20 but yieldable to permit said link to move in the other extreme position when said lever is engaged by said sheave.

16. In a tape control device, the combination with a driving shaft, of a tape pulling sheave 25 rotatably mounted on said shaft, and means including a floating clutch member rotatably mounted on said shaft having one face thereof engaging an adjacent face of said sheave, said clutch member being rotatable independent of 30 said sheave and shaft, said means normally anchoring said sheave to said driving shaft but yieldable to release said sheave when the discharge of the tape is arrested and again to anchor 35 said sheave to said shaft when the discharge of the tape is resumed.

17. In a tape control device, the combination with a driving shaft, of a tape pulling sheave rotatably mounted on said shaft, a drum fixed to said shaft, a disc rotatably mounted on said shaft, an arm pivotally connected to said disc, means for frictionally maintaining said arm in clutching engagement with said drum, and a projection formed on said sheave cooperating with 40 said arm to cause said arm to clear said drum when the discharge of the tape is arrested.

18. In a tape control device, the combination with a driving shaft, of a tape pulling sheave rotatably mounted on said shaft, a clutching lever, means 50 for rotatably mounting said lever on said shaft, and movable independent of said sheave and said driving shaft, and means for normally urging said lever into clutching engagement with said drum and said sheave but yieldable to release said drum 55 when the discharge of the tape is arrested and again to urge said lever into clutching engagement with said drum when the discharge of the tape is resumed.

19. In a tape control device for a stock quota- 60 tion projection machine, the combination with a driving shaft, of a tape pulling sheave rotatably mounted on said shaft, a clutching drum fixed to said shaft, said drum having an uninterrupted cylindrical surface, and a yieldable device inde- 65 pendent of said sheave, said yieldable device being operatively connected to said sheave and normally frictionally engaging the cylindrical surface of said drum but yieldable to disengage said drum when the rotation of the sheave is arrested. 70

20. In a tape control device for a stock quota- 75 tion projection machine, the combination with a driving shaft, of a hollow tape pulling sheave rotatably mounted on said shaft, a drum fixed to said shaft and disposed inside of said sheave, 75

said drum having an uninterrupted cylindrical surface, and a clutching device independent of said sheave, said clutching device being disposed between said drum and said sheave operatively connected to said sheave and normally frictionally engaging the cylindrical surface of said drum but yieldable to disengage said drum when the rotation of the sheave is arrested.

21. In a tape control device, the combination with a driving shaft, of a tape pulling sheave rotatably mounted on said shaft, a clutching drum fixed to said shaft and having an uninterrupted cylindrical surface, a yieldable device independent of said sheave, and means for operatively connecting said yieldable device to said sheave, said yieldable device normally frictionally engaging the cylindrical surface of said drum but yieldable to release said drum when the rotation of the sheave is arrested.

22. In a tape control device, the combination with a driving shaft, of a hollow tape pulling sheave rotatably mounted on said shaft, a drum fixed to said shaft and disposed inside of said sheave, said drum having an uninterrupted cylindrical surface, a clutching device independent of said sheave and disposed between said drum and said sheave, and means for operatively connecting said clutching device to said sheave, said clutching device normally frictionally engaging the cylindrical surface of said drum but yieldable to release said drum when the rotation of the sheave is arrested.

23. In a tape control device, the combination with a tape puller, of a driving shaft, a drum fixed to rotate with said shaft, a friction element, a pivotally mounted arm operatively associated with said friction element to control the movement thereof into and out of frictional engagement with said drum, means operatively associating said arm with said puller, and a spring for urging said arm to effect the movement of said friction element into frictional engagement with said drum said spring being yieldable to respond to the tension in the tape exercised on said tape puller to enable said arm to effect the movement of said friction element to release said drum.

24. In a tape control device, the combination with a tape puller, of a driving shaft, a drum fixed to rotate with said shaft, a friction element, a pivotally mounted arm operatively associated with said friction element, means operatively associating said arm with said puller, and means operatively associated with said arm for actuating said friction element into and out

of frictional engagement with said drum, said means including a spring for urging the arm in one direction, which spring is yieldable to respond to the tension in the tape exercised on said tape puller to urge the arm to yield in the opposite direction.

25. The combination with a support to which tape is intermittently fed, of a tape puller, a driving shaft, a drum fixed to rotate with said shaft, a friction element, a pivotally mounted arm operatively associated with said friction element, means operatively associating said arm with said tape puller, means operatively associated with said arm for actuating said friction element into and out of frictional engagement with said drum, said means including a spring for urging the arm in one direction when tape is supplied to said support and which spring is yieldable to respond to the tension in the tape exercised on said tape puller when the tape supply is interrupted to enable the arm to yield in the opposite direction, and means for effecting a drag on the tape at the anterior end of the support to iron out any vibrations transmitted thereto and to cooperate with said spring to maintain the tape smooth at said support when the intermittent feed to the support is interrupted.

26. The combination of a driving member having a predetermined driving force, a tape puller, intermediate driven means normally drivably connected to said driving member but yieldable to an arresting force to be released from said driving member, and means associating said puller with said intermediate driven means effective to drivably connect said puller with said intermediate driven means or to respond to an arresting force exercised on said puller to release said driven means from said driving member and thereby to enable said puller to come to rest.

27. The combination of a driving member having a predetermined driving force, a tape puller, an intermediate driven means, a spring normally drivably connecting said driven means to said driving member but yieldable to an arresting force to release said driven means from said driving member, and means associating said puller with said intermediate driven means effective to drivably connect said puller with said intermediate driven means or to respond to an arresting force exercised on said puller to oppose said spring in turn to release said driven means from said driving member and therewith to enable said puller to come to rest.

AUGUST D. EITZEN. 55
